(57) **CLAIM**

The ornamental design for a display screen or portion thereof with a graphical user interface, as shown and described.

DESCRIPTION

The sole FIGURE is a display screen or portion thereof with a graphical user interface showing the new design. The outermost broken line illustrates the display screen or portion thereof. The remainder of the broken lines illustrate portions of the graphical user interface. None of the broken lines form part of the claimed design.

1 Claim, 1 Drawing Sheet
